UNITED STATES PATENT OFFICE.

JAMES M. HUNTER, OF ST. LOUIS, MISSOURI, ASSIGNOR TO THE AMERICAN BOLSTER SPRING COMPANY, OF SAME PLACE.

BOLSTER-SPRING FOR WAGONS.

SPECIFICATION forming part of Letters Patent No. 380,574, dated April 3, 1888.

Application filed January 10, 1888. Serial No. 260,346. (No model.)

To all whom it may concern:

Be it known that I, JAMES M. HUNTER, of the city of St. Louis, in the State of Missouri, have invented a certain new and useful Improvement in Bolster-Springs, of which the following is a full, clear, and exact description, reference being had to the accompanying drawings, forming part of this specification, and in which—

10 Figure I is a perspective view of the upper and lower portions of the box with the springs and connecting-bolts removed. Fig. II is part in side view and part in vertical section with the springs and bolts in place. Fig. III is a 15 top view with a standard in section taken on line III III, Fig. II. Fig. IV is a vertical longitudinal section taken on line IV IV, Fig. III.

15 My invention relates to an improvement in bolster-springs for wagons, and relates particularly to an improvement on Letters Patent granted to Wesley Cole, December 25, 1883, No. 290,860.

20 My invention consists in features of novelty hereinafter fully described, and pointed out in the claims.

25 Referring to the drawings, 1 represents the lower member of a box, which consists of pockets 2 to receive the lower ends of the springs 11, and a web, 3, connecting the pockets. This member is placed over the bolster 4 of the wagon, (see Fig. II,) one pocket fitting on each side of the bolster and the web 3 resting on top of the bolster.

30 35 5 represents ribs or flanges on the pockets, which bear against the bolster and prevent the lower ends of the pockets from bending inward, as they would be liable to do in the absence of these ribs.

40 7 represents strengthening-flanges on the sides of the connecting-web 3.

8 represents perforated lugs extending outward from the top of each pocket.

9 represents the upper member of the box,

which is provided with sockets 10 to receive the upper ends of the springs 11, the lower ends of which fit in the pockets 2, as stated. This member is provided with a recess, 12, to receive the board 13 of the wagon-bed, as shown in Figs. II and IV, and it is also provided with perforated lugs 13 and brackets or projections 14, the latter straddling or embracing the standard 15 of the bolster, as shown in Figs. III and IV.

16 represents connecting-bolts passing through the perforated lugs 8 and 13, and which serve to connect the two members of the box, but which do not prevent the parts from moving to and from each other as the springs compress and expand. These bolts 16 have heads on their upper ends, as shown in Fig. III, and pins 17 are passed through their lower ends.

I claim as my invention—

1. In a bolster-spring, the combination of a box composed of an upper and a lower member, and springs located between the members, the lower member consisting of two pockets united by a web and having flanges 5, substantially as and for the purpose set forth. 70

2. In a bolster-spring, the combination of the box composed of two members and springs located between the members, the lower member consisting of pockets connected by a web having strengthening-flanges 7, substantially as and for the purpose set forth. 75

3. In a bolster-spring, the combination of the springs and box composed of two members, the upper member having projections 14, sockets 10, and perforated lugs 13, and the lower member having perforated lugs 8 and bolts passing through the perforated lugs, substantially as and for the purpose set forth. 80

JAMES M. HUNTER.

In presence of—

SAM'L. KNIGHT,
GEO. H. KNIGHT.
